UNITED STATES PATENT OFFICE.

CORNILL JACKSON, OF KALAMAZOO, MICHIGAN.

COMBINED DRILLING AND GRINDING MACHINE.

Application filed April 18, 1923. Serial No. 633,033.

To all whom it may concern:

Be it known that I, CORWILL JACKSON, a citizen of the United States, residing at the city and county of Kalamazoo, State of Michigan, have invented certain new and useful Improvements in Combined Drilling and Grinding Machines, of which the following is a specification.

This invention relates to improvements in combined drilling and grinding machines.

My improved drilling and grinding machine is especially designed by me for use in garages and the like or for drilling or other work requiring a rotary driven spindle and for valve grinding and the like requiring an oscillating spindle or member.

The main objects of this invention are:

First, to provide an improved motor driven machine of the class described which is very compact and is readily adapted for use of either its rotary spindle or its oscillating spindle.

Second, to provide a combined drilling and grinding machine having few parts and these parts arranged so that they are strong and durable and at the same time may be of comparatively light weight.

Third, to provide a combined drilling and grinding machine in which the moving parts are effectively housed and at the same time are readily accessible.

Fourth, to provide an improved combined drilling and grinding machine having the above advantages which is very simple and economical in its structure.

Further objects, and objects relating to structural details, will definitely appear from the detailed description to follow:

I accomplish the objects of my invention by the devices and means described in the following specification. The invention is clearly defined and pointed out in the claims.

A structure which is a preferred embodiment of my invention is clearly illustrated in the accompanying drawing, forming a part of this application, in which:

Fig. I is a side view of a structure embodying my improvements, a valve grinding tool being illustrated in position by dotted lines in one driven spindle and a chuck being shown in full lines in the other spindle.

Fig. II is a detail vertical section on the line corresponding to line 2—2 of Fig. III,

parts being shown in full lines for convenience in illustration.

Fig. III is a horizontal section on a line corresponding to line 3—3 of Fig. II.

Fig. IV is a horizontal section on a line 60 corresponding to line 4—4 of Fig. II.

Fig. V is a side elevation partially in vertical section of a modified form of my invention.

Fig. VI is a horizontal section on a line 65 corresponding to line 6—6 of Fig. V.

In the drawing similar reference characters refer to similar parts throughout the several views, and the sectional views are taken looking in the direction of the little 70 arrows at the ends of the section lines.

Referring to the drawing, I provide a frame or support comprising a body member 1 having a gear box 2 formed in the upper side thereof and a downwardly facing seat 3 for the motor housing 4, the motor housing being clamped in position on this seat by screws as 5 arranged through the flanges 6 on the body member.

The body member 1 is provided with a bearing extension 7 in which the spindles 8 and 9 are mounted in parallel relation, as shown in Fig. II. These spindles 8 and 9 are provided with sockets or chucks 10 and 11 respectively. The socket 11 is internally threaded to receive the stem of a drill chuck shown conventionally at 12. The socket 10 is adapted to receive the shank 13 of the valve grinding tool 14, and has longitudinal slots 15 adapted to receive the pins 16 of the shank 13, the shank being provided with a spring catch 17 adapted to snap over the rib 18 which constitutes a keeper for the catch.

The spindles are provided with suitable 95 bearing bushings 19.

The motor shaft 20 projects into the gear box 2 and is provided with a pinion 21. The motor housing is provided with a bearing extension 22 which fits into an opening 100 23 in the body member 1 thereby aligning the shaft and supporting the housing laterally.

In the preferred embodiment of my invention shown in Figs. I to IV inclusive, a gear 24 having an eccentric 26 on its underside is mounted on the spindle 9 and meshes with the pinion 21 so that the spindle 9 is driven with a continuous rotary movement. The spindle 8 is provided with a crank 25 co-

acting with the eccentric 26 so that as the gear is revolved an oscillating movement is imparted to the spindle 8.

The top member 27 constitutes a cover for the gear box and is provided with a handle 28 for the manipulation of the machine. The top member is provided with a thrust bearing member 29 for the spindle 9.

This top member is also provided with a chamber 30 in which the switch for controlling the motor is placed, the switch mechanism being shown conventionally at 31.

The electric cable for the motor is introduced through an opening 32 in the body member 1.

With this arrangement of parts the machine may be readily adapted for use for drilling or for valve grinding or other purposes requiring oscillating movement.

The machine is very compact and economical in structure, there being relatively few parts and these may be of substantial size.

25 In the modification shown in Fig. V, the parts are arranged in the same general relation as in the structure described, the gear 33 corresponding to the gear 24, being a plain gear, the spindle 34 corresponding to the spindle 8 and being extended so that its crank 35 is in a plane above the gear 32. This necessitates a structure of larger dimensions as the spindles must be farther apart in order to permit the spindle 34 to project at the edge of the gear 33. The crank 35 is connected by the link or pitman 36 to a wrist pin 37 on the top of the gear 33. The crank 35 is longer than the radius of the wrist pin 37 so that the same oscillating movement is secured for the shaft 34 as in the construction of Figs. I to IV, inclusive.

I have not illustrated or described certain other modifications and adaptations which 45 I contemplate as I believe the disclosure made will enable those skilled in the art to which my invention relates to embody or adapt the same as may be desired.

Having thus described my invention, what 50 I claim as new and desire to secure by Letters Patent, is:

1. The combination of a frame comprising a body member provided with a gear box and having a motor housing seat on its underside and a spindle bearing extension disposed at the side of said seat, a top member constituting a cover for said gear box and provided with a hand piece, a motor provided with a housing mounted on said seat, said motor being provided with a shaft projecting into said gear box and having a pinion thereon, spindles mounted in parallel relation on said spindle bearing extension to project into said gear box, one of said spindles being provided with a crank, and

a gear mounted on the other of said spindles and meshing with said pinion on said motor shaft, said gear being operatively connected to said spindle crank.

2. The combination of a frame comprising a body member provided with a gear box and having a motor housing seat on its underside and a spindle bearing extension disposed at the side of said seat, a motor provided with a housing mounted on said seat, said motor being provided with a shaft projecting into said gear box and having a pinion thereon, spindles mounted in parallel relation on said spindle bearing extension to project into said gear box, one of said spindles being provided with a crank, and a gear mounted on the other of said spindles and meshing with said pinion on said motor shaft, said gear being operatively connected to said spindle crank. 75

80 3. The combination of a frame comprising a body member provided with a gear box, a top member constituting a cover for said gear box and provided with a hand piece, a motor mounted on said body member and provided with a shaft projecting into said gear box and having a pinion thereon, spindles disposed on said frame to project into said gear box, one of said spindles being provided with a crank, and a gear mounted on the other of said spindles and meshing with said pinion on said motor shaft, said gear being operatively connected to said spindle crank. 85

90 4. The combination of a frame comprising a body member provided with a gear box, a motor mounted on said body member and provided with a shaft projecting into said gear box and having a pinion thereon, spindles disposed on said frame to project into said gear box, one of said spindles being provided with a crank, and a gear mounted on the other of said spindles and meshing with said pinion on said motor shaft, said gear being operatively connected to said spindle crank. 100

105 5. The combination of a frame, a pair of spindles carried thereby and disposed side by side in parallel relation, a gear mounted on one of said spindles to overhang the other and provided with an eccentric on its underside, such overhung spindle being provided with a crank coacting with said eccentric whereby the spindle on which the gear is mounted is driven with a continuous rotary motion and the spindle having the crank is driven with an oscillating motion. 110

115 6. The combination of a frame, a pair of spindles disposed thereon side by side, one of said spindles being provided with a crank, a gear mounted on the other spindle and provided with an eccentric coacting with said crank so that on the continuous rotation of the gear the spindle on which the gear is mounted is driven with a continuous ro- 120 125

tary motion and the spindle having the crank with an oscillating motion, and means for driving said gear.

7. The combination of a frame comprising a body member provided with a gear box, a motor mounted on said body member and provided with a shaft projecting into said gear box and having a pinion thereon, spindles disposed on said frame to project into said gear box, one of said spindles be-

ing provided with a crank, and a gear mounted on the other of said spindles and meshing with said pinion on said motor shaft, said gear being operatively connected to said spindle crank whereby an oscillating movement is imparted to one spindle and a rotary motion to the other. 15

In witness whereof, I have hereunto set my hand.

CORWILL JACKSON.
